CASTING MOLD

Fred M. Poe, Suffern, N. Y., assignor to The American Brake Shoe and Foundry Company, New York, N. Y., a corporation of Delaware

Original application March 7, 1931, Serial No. 520,782. Divided and this application August 16, 1933, Serial No. 685,332

5 Claims. (Cl. 22—91)

This application is a division of my application Serial No. 520,782, filed March 7, 1931.

The invention relates to casting molds of that class commonly referred to as repetition or permanent molds and which are intended for use in the manufacture of railway brake shoes and other castings produced in large quantities.

The object of the invention is to provide a pivoted mold which can be swung between horizontal and vertical positions and to simplify and facilitate the casting operation by pivoting the drag of the mold upon a support and providing the cope with clamping means for engagement with the pivot of the drag to secure the cope upon the drag and to the mold support at the pivot of the drag whereby the cope is firmly and rigidly secured upon the drag to the pivot of the drag.

And a further object of the invention is to provide simple and convenient means for facilitating the use of the mold and for supporting the cope detached from the drag.

In the accompanying drawing illustrating a selected embodiment of the invention

Fig. 1 is a side view of the mold showing it in broken lines in horizontal position and in full lines in vertical pouring position.

Fig. 2 is a sectional view on the line 2—2 of Fig. 1 showing the drag in elevation.

Referring to the drawing, the mold support comprises a base 3, upright brackets 4, 4 mounted on the base and providing bearings 5, 5 in which the trunnions 6, 6 of the drag 7 are journaled so that the mold may be swung between horizontal position as shown in broken lines in Fig. 1 and vertical position as shown in full lines. To retain the mold in horizontal or vertical position a spring-pressed pin 8 mounted in one of the brackets 4 extends into one of suitably located openings 9 in the adjacent side wall of the drag.

The drag comprises a metal shell 10 having a refractory block 11 and metal chill blocks 12, 12 arranged therein. The chill blocks are clamped against the ends of the refractory block by adjusting bolts 13 mounted in the end walls of the shell and bearing against the chill blocks. The cope comprises a metal shell 14 having a refractory block 15 arranged therein. The mold cavity 16 is located partly in the cope and partly in the drag and the pouring gate 17 at one end of the mold communicates with one end of the mold cavity. The engaging faces of the cope and drag are disposed in flat intersecting planes extending at an angle somewhat similar to the curvature of the mold cavity to enable the parting defined by the engaging faces of the cope and drag to

intersect the mold cavity throughout its length and to properly seat the cope on the drag and effect registration thereof. Pins 19 mounted in ears 18 on the side walls of the drag are arranged to engage openings in ears 20 on the side walls of the cope as a further means of registering the cope and drag.

It is important to provide means for locking the cope tightly and in fixed position upon the drag to swing therewith into pouring position and into horizontal position, after the pouring operation is completed, for removal of the cope and the casting; and it is important that the fastening or securing means should be capable of easy manipulation, that they should be strong and substantial to prevent separation of the cope from the drag which would result in the formation of fins at the parting and objectionable deformation of the casting; and it is also desirable that the weight of the cope and of that part of the casting therein be sustained from the support instead of from some part of the shell of the drag. With these ends in view I have provided studs 21 on the side walls of the cope and pivotally mount clamps 22 thereon, these clamps having hooked ends which are adapted to be engaged with the trunnions 6 between the side walls of the shell of the drag and the bearings 5 in the supporting brackets 4 whereby the cope is clamped securely and rigidly upon the drag and the clamping means are engaged with the trunnions of the drag at the bearings in the supporting brackets. The hooked ends of the clamps engage the trunnions and the trunnions are journaled in the bearings so that the clamps will not become loosened or disengaged when the mold is being turned between vertical and horizontal positions. The pivot studs 21 of the clamps are located in substantial alinement with the pivot trunnions of the drag and mold and when the clamp hooks engage the trunnions the weight of the cope and that part of the casting therein will be sustained through the trunnions by the supports.

It is necessary to replace and remove the cope for each casting operation. The cope is heavy and the casting operation is conducted in the presence of a high degree of heat and it is desirable to facilitate the handling of the cope in every possible way for efficient results; and for this purpose I provide a rest 23 on the base 3 and feet 24 on the end of the cope opposite the pouring gate and handles 30 on the cope. The handle ends of the hook clamps may be operated to release the clamps from the trunnions, after the mold has been swung to horizontal position and

fastened in this position, and then the cope may be lifted from the drag and set with its feet 24 upon the rest 23 at the side of the drag. This is a convenient position for inspection of the mold cavity in the cope and for the insertion of inserts 6 in the cope for embedment in the casting if so required. Such inserts are held in the cope by a wire 25 which extends through the wall of the cope and passes over the grooved cam 26 mounted on the shaft 27 journaled in brackets 28 on 10 the cope. The shaft 27 is operated by a crank 29 to tighten the wire 25 and hold the inserts (not shown) in position against the top wall of the mold cavity in the cope. In preparing for a casting 15 operation the drag should be secured in horizontal position, whatever inserts are to be embedded in the casting should be secured in place in the mold cavity and to the cope or to the drag, or to both, and then the cope is seated upon the drag and secured thereto. If it should be required 20 to treat the walls of the mold cavity by cleaning or spraying it should be done before the cope is assembled with the drag. After the assembly is completed and the cope locked in place 25 the mold is swung to and secured in a vertical position and the molten metal is poured into the mold cavity through the pouring gate. After the molten metal has sufficiently solidified the mold is swung to horizontal position, the wires 30 securing the inserts are clipped, the cope is removed and placed in standing position on the rest 23, the casting is removed from the drag, and the mold is prepared for the next pouring operation.

I have illustrated and described a selected embodiment of the invention which has been found to be satisfactory in practical use but I do not wish to be limited to the precise details of construction herein shown and described but reserve the right to make such changes and alterations as 35 fall within the scope of the following claims:

I claim:

1. A repetition casting mold comprising a support, a drag pivoted to swing between horizontal and vertical positions in said support, a cope for 45 the drag, and means pivotally mounted on the cope and operatively engaging the pivot of the drag to clamp the cope on the drag and sustain the weight of the cope and the part of the cast-

ing contained therein from the support during pivotal movement of the drag and cope.

2. A repetition casting mold comprising a support, a drag pivoted to swing between horizontal and vertical positions in said support, a cope for 5 the drag, and hook clamps pivotally mounted on the cope and operatively engaging the pivot of the drag to clamp the cope on the drag and sustain the weight of the cope and the part of the casting contained therein from the support during pivotal movement of the drag and cope. 10

3. A repetition casting mold comprising a support having bearings therein, a drag, trunnions on the drag journaled in said bearings to support the drag for pivotal movement between horizontal and vertical positions, a cope for the drag, and means pivotally mounted on the cope and operatively engaging the trunnions for clamping the cope on the drag and sustaining the weight of the cope and the part of the casting contained 15 therein from the support during pivotal movement of the drag and cope.

4. A repetition casting mold comprising a support having bearings therein, a drag, trunnions on the drag journaled in said bearings to support 25 the drag for pivotal movement between horizontal and vertical positions, a cope for the drag, and clamps pivotally mounted on the cope at the sides thereof and having operating handles at one end and hooks at the other end to engage the trunnions and secure the cope on the drag so that the 30 weight of the cope and that part of the casting therein will be sustained from the support during pivotal movement of the drag and cope.

5. A repetition casting mold having a base, supporting brackets on the base having bearings, a rest on the base at one side of said brackets, a drag, trunnions on the drag journaled in said 35 bearings, a cope adapted for cooperation with the drag, feet on one end of the cope, and clamps 40 pivotally mounted on the cope and engaging said trunnions to clamp the cope on the drag, said clamps being detachably engaged with the trunnions to permit removal of the cope from the drag and disposal of the cope with its feet engaging 45 said rest to support the cope alongside the drag in position for repetition of a casting operation.

FRED M. POE.
